UNITED STATES PATENT OFFICE.

WILLIAM ARTHUR HILDYARD AND ALEXANDER BROWN DRUMMOND, OF
CROUCH END, ENGLAND.

DOOR CLOSER AND STOP.

No. 823,532.

Specification of Letters Patent.

Patented June 19, 1906.

Application filed May 13, 1905. Serial No. 260,360.

To all whom it may concern:

Be it known that we, WILLIAM ARTHUR HILDYARD and ALEXANDER BROWN DRUMMOND, jewelers, subjects of the King of Great Britain, both residing at 40 Topsfield Parade, Crouch End, in the county of Middlesex, England, have invented certain new and useful Improvements in Door Closers and Stops, of which the following is a specification.

This invention relates to a device adapted for holding a door in the open position or for closing it, as desired. The invention is also applicable as a door-stop.

The device is composed of two parts, one in the form of a keeper with a T-shaped slot, which is secured on the door. The other part is a spring-mounted arm pivoted to a base-plate secured to the door-post and terminating at its forward end in a bent-over double shoulder having a central tongue, pin, or projection adapted to engage with the slot in the keeper.

In the accompanying drawings, Figure 1 is an elevation showing part of a door and door-post with our invention fitted thereto, and Figs. 2 and 3 are respectively longitudinal and transverse sections taken on the lines 2 2 and 3 3 of Fig. 1. Fig. 4 is an end elevation showing the parts in the held-open position. Fig. 5 is a bottom plan view of Fig. 1, and Fig. 6 is a section on the line 6 6 of Fig. 5.

The same parts are lettered to correspond in all six figures.

In the drawings, *a* is the keeper, having a T-shaped slot *a'*, and *b* is the door to the back or rear side of which the keeper is secured by the screws *b'* or by other suitable means.

c is the spring-mounted arm, which is pivoted to the base-plate *d* so that said arm *c* can only turn through a right angle or thereabout. The device thus acts as a door-stop.

e is the door-post, to which the base-plate *d* is secured by the screws *e'* or by other suitable means.

f is a spring, which may be a coiled spring, as shown, or of any suitable character and arranged so as to keep the arm *c* down in the position shown in Fig. 2.

The forward end of the arm *c* is bent over and terminates in a double shoulder *c'* *c''*, having a central tongue, pin, or projection *c'*, which engages in the longitudinal part of the

T-shaped slot in the keeper, the first shoulder *c'* acting as a stop preventing the forward end of the arm from passing into the longitudinal part of the slot. The transverse part or head *a''* of the slot is wide enough to admit the thickened part *c'* between the shoulders *c'* and *c''* on the downwardly-bent forward end of the arm *c*.

The parts are arranged so that the central tongue, pin, or projection *c'* is always engaged with the longitudinal part of the T-shaped slot *a'* in the keeper *a*, the shoulder *c'* resting on the top of said keeper. When the door *b* is opened sufficiently, the head *a''* of the T-shaped slot is engaged by the first step or thickened part *c'* between the double shoulder *c'* and *c''*, the second shoulder *c''* acting as a final stop, as shown in Fig. 4. In this position the arm *c* is held in the head of the slot by the fact that these two parts, the arm and the transverse slot, are moving in arcs about different centers, which arcs overlap at the point of contact of the arm and slot; but as the connection is only by contact the arm will be released by a slight push on the door in the direction of closing, whereupon the tongue *c'* reenters the longitudinal part of the slot *a'* and the shoulder *c'* again rests on the top of the keeper *a* and the arm then acts by the pressure of its spring to close the door in the ordinary way. The spring-arm may be adjusted as desired by means of a set or other screw *g*, engaging a threaded hole in the base-plate *d*, carrying the arm *c*.

If desired, the central tongue *c'* and the longitudinal part *a'* of the slot in the keeper *a* may be dispensed with, as their only function is to act as guides to cause the arm *c* to travel in a straight line to the transverse slot *a''* in the keeper; also, the arm *c* may have a roller to bear on the keeper *a*, the latter being provided with a recess to receive it when the end of the arm *c* falls into the transverse slot *a''*, but we prefer the arrangement shown and described.

Having fully described our invention, what we claim, and desire to secure by Letters Patent, is—

The combination with a hinged door and its post, of a device for holding open and closing said door comprising a keeper secured to the rear side or back of the door and provided with a slot, a base-plate secured to the

door-post, an arm pivotally connected with said base-plate and having at its forward end a downwardly-bent shouldered portion adapted to ride on the keeper during the opening of the door and to engage in the slot in said keeper when the door is opened to a predetermined extent and to be automatically disengaged from said slot when the door is moved slightly in the direction of closing, and a spring arranged to effect the full closing of the door when the shouldered portion of

the arm has been disengaged from the slot in the keeper, substantially as described.

In testimony whereof we have hereunto set our hands, in presence of two subscribing witnesses, this 28th day of April, 1905.

WILLIAM ARTHUR HILDYARD.
ALEXANDER BROWN DRUMMOND.
